(57) **CLAIM**

The ornamental design for a baseball/softball score keeping device, as shown and described.

DESCRIPTION

FIG. 1 is a perspective view of a baseball/softball score keeping device showing my new design;

FIG. 2 is a front elevational view thereof;

FIG. 3 is a left side elevational view thereof, the right side elevational view being a mirror image thereof; and,

FIG. 4 is a rear elevational view thereof.

The broken lines are for illustrative purpose only and from no part of the claimed design.
